WITNESS:

UNITED STATES PATENT OFFICE.

HENRY A. STEWART, OF HIGHLAND PARK, MICHIGAN.

GRINDING TABLE.

Application filed December 26, 1923. Serial No. 682,805.

To all whom it may concern:

Be it known that I, HENRY A. STEWART, a citizen of the United States, residing at Highland Park, in the county of Wayne and State of Michigan, have invented new and useful Improvements in Grinding Tables, of which the following is a specification.

This invention relates to a grinding device for grinding ball bearings, the general object of the invention being to provide a table which has guiding means associated therewith for causing the balls to pass in a circuitous path from the outer edge of the table to a point adjacent the center so that they will remain in contact with the grinding wheel for a long time.

Another object of the invention is to so form the parts that the balls can be fed to the grinding apparatus in a continuous stream and without stopping the machine to reload it.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a side view of the apparatus. Figure 2 is a sectional view thereof.

Figure 3 is a top plan view of the table.

Figure 4 is a plan view of the guiding member.

Figure 5 is a plan view of the entire device.

Figures 6 and 7 are views of a modification.

In these views, 1 indicates a base in which the table 2 is located and is held therein by the bolts 3. A disc-shaped guiding member 4 is held on the base 1 by the bolts 5 and this member covers the table. The grinding wheel is shown at 6. The guiding member is provided with a spiral-shaped slot 7 which has its mouth 8 at the outer edge of the member and the balls to be ground are fed

into said mouth by the tube 9. The inner end of the slot is arranged to feed the balls to the outlet opening 10 formed in the table 55 adjacent the center thereof. The table has its upper surface tapered, as shown at 11, this taper being so formed that it will gradually force the balls against the wheel 6 as the balls pass around the slot 7 towards the outlet opening 10 and are caused to ride up the surface by said slot. The rotary movement of the grinding wheel forces the balls through the slots 7 to said opening. The tapered part of the table gradually 60 forces the balls against the wheel so that they will be ground to the proper size by the time they reach the outlet opening. The taper of the table must be such as to give the balls the proper diameter by the time 70 they reach the outlet opening.

Instead of using the guiding member the table can be provided with a groove 12, as shown in Figures 6 and 7 which takes the place of the guiding member.

It is thought from the foregoing description that the advantages and novel features of my invention will be readily apparent.

I desire it to be understood that I may make changes in the construction and in the 80 combination and arrangement of the several parts, provided that such changes fall within the scope of the appended claims.

What I claim is:—

1. A ball grinding machine comprising a 85 table, a grinding wheel located above the same and means for guiding balls in a circuitous path around the table and under the wheel, said table being tapered to gradually force the balls against the grinding wheel. 90

2. A grinding machine comprising a table having an inlet adjacent its outer edge and an outlet adjacent its center, a grinding wheel located above the table, guiding means for causing the balls to pass in a circuitous path on the table from the inlet to the outlet while they are being acted upon by the grinding wheel and said table being tapered to gradually force the balls against the grinding wheel. 100

3. A grinding machine comprising a table having an inlet adjacent its outer edge and an outlet adjacent its center, a grinding wheel located above the table, guiding means

for causing the balls to pass in a circuitous path on the table from the inlet to the outlet while they are being acted upon by the grinding wheel, said table being tapered to gradually force the balls against the grinding wheel, such guiding means consisting of a dislike member placed between the table

and grinding means and having a spiral-shaped slot therein through which the balls pass.

10

In testimony whereof I affix my signature.

HENRY A. STEWART.
